FIG. 3

FIG. 4

FIG. 1 is a perspective view of a chair base or similar article embodying my new design;

FIG. 2 is a top plan view of the chair base or similar article as it appears in FIG. 1;

FIG. 3 is a bottom plan view thereof; and

FIGS. 4 and 5 are sections along lines 4—4 and 5—5 respectively of FIG. 2.

The characteristic feature of my device resides in the combination on the metallic base of the configuration disclosed, having a low arched planar upper surface and substantially straight-webbed bottom surface, said upper surface having a contrasting wood inlay, all as shown.

I claim:

The ornamental design for a chair base or similar article, substantially as shown and described.
